UNITED STATES PATENT OFFICE.

EDWIN COMER SMITH, OF BALTIMORE, MARYLAND.

LIQUID SEPARATOR.

Application filed August 5, 1924. Serial No. 730,217.

My invention relates to machines of that class which are adapted to effect separation of fluids, and particularly pertains to machines of the type in which separation of liquids is accomplished by flotation.

An object of my invention is to provide a means whereby floating substances may be separated and removed from the liquid on which they float and which is especially adapted for use in accelerating the discharge of viscous fluids from an over flow outlet such for example as in effecting the evacuation of froth from flotation machines.

Another object is to provide a device of the above character which is adapted to be adjusted to meet varying conditions and which is simple in construction and efficient in operation.

With the foregoing objects in view together with such other objects and advantages as may subsequently appear, the invention resides in the parts and in the combination, construction and arrangement of parts hereinafter described and claimed and illustrated by way of example in the accompanying drawings, in which:

Figure 1 is a plan view of a flotation machine showing the invention as applied thereto;

Figure 2 is a view in vertical section as seen on the line 2—2 of Figure 1;

Figure 3 is a detail and vertical section of the evacuator illustrating its principle of operation;

Figure 4 is a detail in section as seen on the line 4—4 of Figure 2;

Figure 5 is a detail in plan as seen on the line 5—5 of Figure 3.

Referring to the drawings more specifically, 5 indicates a suitable type of flotation machine to which the invention is applied and which machine embodies an aerating chamber 6 containing an aeration drum 7 and also includes a frothing chamber 8; there being an inlet opening 9 to the aerating chamber communicating with a feed conduit 10 fitted with a slide valve 11 for regulating the feed of the materials to be treated to the aerating chamber and there being a restricted tailing discharge pipe 12 leading from the frothing chamber 8. The aerating chamber operates to form a froth which is delivered to the frothing chamber 8 through an outlet 14 leading from the upper portion of the former chamber and opening to a downwardly extending passage 15

communicating with the frothing chamber 8. The froth accumulating in the frothing chamber is designed to be discharged over a ledge 16 located at the upper margin of the front wall 17 of the frothing chamber and thence pass to a trough 18 extending along the ledge 16 and leading to any suitable point of discharge.

In carrying out my invention a rotary cylinder or roller 19 is arranged to extend longitudinally of the open upper end of the frothing chamber adjacent to and parallel to the inner margin of the ledge 16 and spaced therefrom; the ledge being inclined downwardly from near the periphery of the roller 19.

The roller 19 is provided with trunnions 20 at its ends which are journaled in suitable bearings 21 carried on the end walls 22 of the frothing chamber.

One of the trunnions is fitted with a pulley 23 or other suitable driving means adapted to be operated from any suitable source of power to effect rotation of the roller.

Mounted on the ledge 16 is a scraper or wiper 24 one edge of which is arranged to extend in close proximity to the outer perimeter of the roller 19 and may in some instances be disposed in sliding contact therewith.

This scraper or wiper may constitute a metallic plate or a strip of fibrous material such as wood, leather or heavy fabric and may be formed in one or more pieces being here shown extending continuously throughout the length of the roller 19.

The scraper is preferably adjustable so that it may be shifted to various positions transversely of the ledge 16 whereby its inner edge may be disposed in various relations to the roller 19, as occasion may require. For this purpose the scraper is here shown as formed with transverse slots 25 through which extend set screws 26 engaging the ledge 16 and having head portions adapted to engage the upper face of the scraper. The screws 26 on being loosened permit the scraper to be moved transversely within the limits of the slots 25.

The roller 19 is preferably mounted for vertical adjustment and for this purpose is here shown as having its bearings 21 slidably supported in vertical guide ways 27 formed in the end walls 22 of the frothing chamber; the bearings being supported by a swivel connection 28 on a screw 29 threaded

on and carried by a plate 30. By this construction the roller 19 may be raised or lowered by adjusting the screws 29 so that it may be immersed more or less in the liquid 5 to be discharged and whereby the area of surface contact of the roller with the liquid may be increased or diminished as occasion may require.

In the operation of the invention the 10 roller 19 is rotated in the direction indicated by the arrow *a* in Figures 2 and 3 and by reason of being disposed so that its outer perimeter will contact the froth accumulating in the upper portion of the frothing 15 chamber will act to convey the froth to discharge because of the inherent tendency of the froth to adhere or cling to the surface of the roller; the viscous character of the froth causing a considerable volume thereof to be 20 moved under the impetus of the roller and to be carried up and over the roller onto the scraper and ledge from whence it flows into the discharge trough 18. The scraper 24 serves to remove the froth from the roller 25 and to direct it down the inclined ledge to the trough.

From the foregoing it will be seen that by employing the rotating roller the discharge of the froth from the frothing chamber will 30 be augmented and accelerated in comparison with what would ordinarily be the normal flow of the froth from the frothing chamber it being well known that in the operation of machines of this character the froth tends 35 to accumulate and to pile up at the upper end of the frothing chamber and there break down and thicken so that its flow from the frothing chamber will be greatly retarded.

While I have shown and described the invention as applied to the evacuation of froth 40 it is not limited to this particular use as it is also adapted to be employed in separating any floating substances from a surface of liquid in which the roller may be partly submerged and especially in effecting the separation of a viscous liquid that would cling to the roller, and while I have shown and described a specific embodiment of my invention, I do not limit myself to the exact details of construction or arrangement shown but may employ such modifications and changes as come within the spirit and scope 50 of the invention as set forth in the appended claims.

I claim:

1. In a machine for separating liquids, a liquid containing chamber having an overflow discharge opening provided with a ledge, a partially submerged horizontal roller arranged in said opening in operative relation to said ledge, and means carried by said ledge for wiping liquid from said roller and directing the liquid thus removed to discharge over said ledge.

2. In a machine for separating liquid, a liquid-containing chamber having an overflow discharge opening provided with a ledge, a partially submerged horizontal roller arranged in said opening in operative relation to said ledge, means for wiping liquid from said roller and directing the liquid thus removed to discharge over said ledge, and means for adjusting said roller vertically to vary the extent of its submersion in the liquid in said chamber.

EDWIN COMER SMITH.
